INTERMEDIATE SUPPORT FOR VENETIAN BLIND TILT RAILS

Filed Oct. 25, 1928

UNITED STATES PATENT OFFICE

FRANK LEEPER, OF SAN MARINO, CALIFORNIA, ASSIGNOR TO COLUMBIA MILLS INCORPORATED, OF NEW YORK, N. Y., A CORPORATION OF NEW YORK

INTERMEDIATE SUPPORT FOR VENETIAN-BLIND TILT RAILS

Application filed October 25, 1928. Serial No. 314,869.

This invention relates to improvements in Venetian blinds, the essential elements of which consist of a head rail adapted to be rigidly secured at the top of a window or 5 the like, and a depending tilt rail from which a series of horizontal thin slats are adjustably supported by means of web straps which hang vertically down from the tilt rail, and means to effect an angular tilting of the tilt 10 rail and horizontal slats, as well as vertical movement of one or all of the horizontal slats to open or partially open position.

The tilt rail is pivotally supported at its ends on supporting members secured to the 15 head rail, and in some cases, particularly in larger windows having a considerable horizontal dimension it is desirable to also pivotally support the tilt rail at the center, or at one or more points intermediate its length.

20 I am aware that several types of intermediate supporting devices for the tilt rails of Venetian blinds have already been used, but in each case the closing of the blind was limited by reason of the construction to tilting 25 offered by the intermediate supporting device. It was, therefore, impossible to completely close the blind, that is, to move the tilt rail and horizontal slat members through 180° or one-half complete turn. The foregoing 30 going slat movement is very desirable, as it enables the operator to completely close the blind against the intrusion of light, or unwanted observation from outside the window so equipped.

35 It is also highly desirable that the intermediate pivotal supporting member be pivotally connected to the tilt rail at a point exactly in line with the axis of rotation of the tilt rail, which is ordinarily substantially at 40 the center of the cross-section thereof.

Therefore, the principal object of this invention is to provide an intermediate pivotal support which is pivotally connected to the tilt rail at substantially the center of the 45 cross-section thereof, and which will permit free angular tilting of the tilt rail and horizontal slat members through substantially a complete half turn or 180°, to effect complete closing of the blind.

50 An advantage, derived from an applica-

tion of this invention to the conventional Venetian blind, is that the blind may be completely closed by tilting the tilt rail 90° from the normal flat-wise position, thus causing the entrained slats to assume the same position and in which the outer marginal edges of the slats are brought to lie one against the other, thus effecting a complete closure of the window or door so protected.

55 Other advantages are simplicity of construction, low cost of manufacture and reliability of operation.

The accompanying drawings illustrate embodiments of my invention and referring thereto:

60 Fig. 1 is a front elevation of a Venetian blind, embodying my invention, and shown in partially closed position, and as mounted in a window casement.

65 Fig. 2 is a vertical section on line 2—2 in Fig. 1.

70 Fig. 3 is a horizontal section on line 3—3 in Figs. 1 and 4, showing central end portions of the tilt rail with the intervening portion broken out.

75 Fig. 4 is a sectional view on line 4—4 in Fig. 3, showing a fragment of the head and tilt rails and showing the intermediate supporting means to permit 180° movement of the tilt rail.

80 Fig. 5 is a view on line 5—5 in Fig. 1, showing mounting and operating means adapted to effect complete 180° rotation of the tilt rail.

85 Fig. 6 is a section on line 6—6 in Fig. 4, showing an assembly of the means to effect complete 180° rotation of the tilt rail.

90 Fig. 7 is similar to Fig. 6, except that the tilt rail is shown in vertical or closed position.

95 1 indicates a window casement having the usual stiles 2 and rails 3, in which is mounted a conventional type of Venetian blind, 4, modified to embrace the invention herewith disclosed.

100 Referring to the blind proper, 5 indicates the head rail, which is secured in position by brackets 6, secured to the stiles 2, or to any other suitable portions of the window casement, and to which a tilt rail 7, is pivotally

mounted by means of brackets 8 and 8', secured to the head rail 5, as by means of screws 9.

Web strips 10 are vertically suspended 5 from the tilt rail 7, and at spaced intervals support thin flat slats 11, which are loosely supported upon transverse webbing strips 10' extending between the vertical strips of webbing and which are at all times parallel 10 with the tilting rails 7.

Tilting cords 12 and 13, are adapted to effect angular movement of the tilting rail 7 and slats 11, and to accomplish this, one of the cords, as 12, is passed over a pulley 14 15 freely rotatable on an axis 15 which is fixed in the bracket 8 by any convenient method, and said cord is then given a single turn 12' about the tilting rail 7 from which the end 13 hangs downwardly, parallel with its other 20 end 12. Means such as a staple 18' prevents slipping of the cords 12 and 13, when the cords are pulled to effect movement of the tilt rail. Any suitable means such as shown for example in Whitmore Patent No. 25 1,639,474 may be provided for tending to hold the tilt rail in any angular position to which it may be tilted.

15 indicates a lifting cord forming a loop 15' and having its ends passing over a pulley 16 while one end passes over pulley 17 and the other over pulley 18, passing down through openings or slots 34 in the tilt rail 7 and in the several slats 11, as shown in Fig. 2, and terminating in a convenient fastening 35 means as a knot beneath the lowermost slat or bottom rail 11' to prevent withdrawal through the slats when the loop 15' is pulled. It is evident that pulling on cords 15 will cause each of the respective slats to be lifted 40 as the lowermost slat or bottom rail comes into contact with and lifts upwardly against the slat immediately above, etc. A post 19 fastened to one of the stiles 2 of the window casement 1 is adapted to receive the cords 15 45 to hold the blind in any position except, of course, closed position, in which position the cord 15 is played out and the weight of the blind rests upon the webbing 10 which is secured, as above stated, to the tilt rail 7.

50 In any intermediate position, the weight of the slats is carried by the lifting cords and is held in that position by securing the cord 15 to the post 19.

In addition to supporting the tilt rail at 55 the ends by means of supporting brackets 8 and 8', I provide according to the present invention, means for rotatably supporting said tilt rail at one or more points intermediate the ends thereof. In the present instance I have shown one of such intermediate supporting means, located at the center of the tilt rail, but it will be understood that any desired number of similar supporting means may be provided at suitable points. Said 60 intermediate supporting means may com-

prise a substantially vertically extending strap or link 20 having its upper end loosely supported in a recess 35 in the head rail by means of a pin 21, which may comprise in practice a screw or nail as shown, passing through a vertical slot 21' in link 20. The lower end of said supporting link is secured by pivot member or pin 22 to the U-shaped portion 27' of a bracket 27 secured to the tilt rail 7. In order to permit placing of the pivot pin 22 at the center of cross-section of the tilt rail and upon the axis of rotation thereof, I prefer to entirely cut away the tilt rail at this point, said tilt rail being thus formed of two parts 24 and 25, and the U-shaped portion 27' of bracket 27 being received between the adjacent ends of said parts as shown particularly in Fig. 4. The two parts of the tilt rail are secured together by means of bracket 27 and a plate 26, both of which may be secured thereto in any suitable manner as by means of screws 28. The plate 26 and bracket 27 are also preferably riveted together as indicated at 29.

The foregoing assembly provides complete freedom of movement in the tilt rail up to 180°, which is as far as it is desirable or possible to go, because at either of the closed positions the overlapping edges of the slats strike one another to prevent further movement.

By referring to Fig. 5, it can readily be seen how the application of power, as a pull, on the tilting cords 12 or 13 will rotate the tilt rail from the horizontal line A—A in Fig. 5, to that coinciding with the dotted line position and the vertical line B—B, thus enabling 90° rotation in either direction from horizontal position or a total of 180° of movement in the tilt rail and the entrained horizontal slots 7 and effecting the complete closing of the space between the slats 7 to the end that light and vision may be entirely cut off by completely closing the blind.

As is evident from Fig. 7, the ability of the tilt rail to swing to a vertical position without interference from the substantially vertical intermediate support is due to the fact that the space 23 between the sides of the U-shaped part 27' of bracket 27 extends to a depth beyond the pivot 22 throughout the width of the tilt rail, so as to receive the link 20 when said tilt rail is swung to such position. The link 20 is preferably made as a flat strip whose lower portion extends with its larger transverse dimension, or width, in a plane perpendicular to the tilt rail, up to a height greater than the distance from the pivot 22 to the edge of the tilt rail, so that the recess 23 need be of only sufficient width to receive the smaller dimension, or thickness, of said strip. The upper portion 20' of said strip, however, is preferably twisted approximately 90° so as to lie in a plane extending longitudinally of the tilt rail, thus present- 125 130

ing the larger transverse dimension of said strip to receive pin 21. While the recess 35 is large enough to loosely receive this upper portion 20' and permit the same to adjust 5 itself to position on pin 21 without liability of binding or sticking, the walls of said recess nevertheless restrain said portion against substantial forward and backward movement, so that the supporting link re- 10 mains in substantially fixed vertical position during tilting of the tilt rail.

By entirely severing the tilt rail at the center, or making the same of the two parts 24 and 25, and placing bracket 27 in position 15 with the U-shaped part thereof extending down between the adjacent ends of said parts, I am thus enabled to place the pivot 22 at substantially the center of cross-section of tilt rail 7, and to permit the tilt rail to swing 20 approximately 90° in either direction from horizontal without striking the supporting link 20, while said bracket, together with plate 26, provides a rigid connection between the two parts of the tilt rail which is fully as 25 strong as though said tilt rail were continuous in one solid piece. Furthermore, I am thus enabled to use shorter pieces of material in making the tilt rail, and the proportion of waste material is therefore reduced.

30 I claim:

1. In a Venetian blind, in combination with a fixed support above the blind, a tilt rail extending beneath said fixed support, means rotatably supporting the ends of said 35 tilt rail, and an intermediate supporting member supported by said fixed support and held thereby in substantially vertical position and pivotally connected to said tilt rail intermediate the ends thereof, the axis of rotation defined by said end supporting and intermediate supporting means extending substantially through the center of cross section of said tilt rail, and said tilt rail being recessed downwardly from its upper edge 40 and throughout its width, so as to receive said intermediate supporting member upon tilting of the tilt rail and permit tilting of said tilt rail to substantially vertical position in either direction.

50 2. In a Venetian blind, in combination with a fixed support, a tilt rail extending beneath said fixed support, means rotatably supporting the ends of said tilt rail, said tilt rail being provided with a recess, intermediate 55 its ends, opening upwardly and extending down beyond the center of cross-section of said tilt rail throughout the width thereof, a vertically extending supporting link having its upper end supported in substantially fixed position upon said fixed support and having its lower end extending within said recess in the tilt rail, and means pivotally connecting the tilt rail to said supporting link.

65 3. In a Venetian blind, in combination with

a fixed support, a tilt rail consisting of two parts placed end to end and spaced somewhat apart, means rigidly connecting the adjacent ends of said parts together, means rotatably supporting the ends of the tilt rail, an intermediate supporting member connected to said fixed support, and means pivotally connecting said supporting member at its lower end to said tilt rail intermediate the adjacent ends of the two parts thereof.

4. In a Venetian blind, a construction as set forth in claim 3, said means connecting together the parts of the tilt rail being provided with a recess extending entirely across the tilt rail and to a depth beyond the center of cross-section, and said intermediate supporting member having its lower end within said recess and pivotally connected at substantially the center of cross-section of the tilt rail.

5. In a Venetian blind, a construction as set forth in claim 3, said means connecting together the parts of the tilt rail comprising a bracket secured to the upper faces thereof and having a U-shaped portion extending downwardly in the space between the two parts of the tilt rail and a plate secured to said intermediate supporting member having its lower end extending within said U-shaped portion and pivotally connected thereto.

6. In a Venetian blind, in combination with a fixed support, a tilt rail extending beneath said fixed support, means rotatably supporting the ends of said tilt rail about an axis of rotation extending longitudinally of the tilt rail and substantially through the center of cross section thereof, said tilt rail being provided with a recess intermediate its ends extending to a depth below said axis of rotation and throughout the entire width of said tilt rail, and intermediate supporting means for said tilt rail, said intermediate supporting means comprising a vertically extending link having its upper end supported in substantially fixed position on said fixed support and having its lower end extending within said recess and pivotally connected to the tilt rail substantially at said axis of rotation, said recess serving to receive the body of said link upon tilting of said tilt rail so as to permit movement thereof about said axis of rotation through an angle of substantially 180° without requiring substantial movement of said link.

7. In a Venetian blind, a fixed head rail, a tilt rail extending beneath said head rail, means rotatably supporting the ends of said tilt rail for rotation about a horizontal axis extending substantially through the center of cross-section thereof, said tilt rail having a recess intermediate its ends and extending throughout its width and from its upper face downwardly below said axis of rotation, an intermediate supporting mem-

ber located intermediate the ends of said tilt rail and comprising a vertically extending link having its lower end extending into said recess in the tilt rail, a pivot member lying substantially in said axis of rotation of the tilt rail and rotatably connecting said tilt rail to the lower end of said link, said head rail being recessed upwardly from its lower face to receive the upper end of said link, 10 said link being twisted intermediate its height and having its lower portion, for a height greater than half the width of the tilt rail, disposed in a plane substantially perpendicular to the length of the tilt rail and its upper 15 portion disposed in a plane substantially parallel to the length of the tilt rail and projecting into said recess in the head rail, and a pin extending transversely in said head rail and through the upper end of said link.

20 In testimony whereof I have hereunto subscribed my name this 15th day of October, 1928.

FRANK LEEPER.
